UNITED STATES PATENT OFFICE

134,515

DESIGN FOR A GAME BOARD

Robert P. Long, Elmhurst, Long Island, N. Y.

Application August 31, 1942, Serial No. 108,081

Term of patent 3½ years

To all whom it may concern:

Be it known that I, Robert P. Long, a citizen of the United States, residing at Elmhurst, L. I., in the county of Queens and State of New York, have invented a new, original, and ornamental Design for a Game Board, of which the following is a specification, reference being had therein to the accompanying drawing forming part thereof, in which the figure is a plan view of a game board, showing my new design, which game board is of no appreciable or substantial thickness; none of the features of the design projects from the surface of the board.

I claim:

The ornamental design for a game board, as shown and described.

ROBERT P. LONG.
